UNITED STATES PATENT OFFICE.

GEBHARD JAEGER, OF COLUMBUS, OHIO.

CONCRETE-MIXING MACHINE.

1,414,648.

Specification of Letters Patent. Patented May 2, 1922.

Application filed September 25, 1920. Serial No. 412,837.

To all whom it may concern:

Be it known that I, GEBHARD JAEGER, a citizen of the United States, residing at Columbus, in the county of Franklin and State of Ohio, have invented a certain new and useful Improvement in Concrete-Mixing Machines, of which the following is a specification.

The invention relates as embodied herein more especially to the type of concrete mixing machine in which the mixing drum has a single opening and mounted upon a frame to swing to one side for charging it with the materials to be mixed and to the opposite side for discharging the mixed materials.

The principal object of the invention is to provide means whereby an automatically measured quantity of water is automatically supplied to the mixing drum while the latter is moving from its discharging position to its charging position so as to save time and avoid the necessity for special attention to the business of supplying the proper quantity of water to the mixing drum. Other objects will appear from the following description.

The invention is embodied in the construction and combinations of parts in the example herein particularly shown and described, the features of novelty being finally claimed.

In the accompanying drawings—

Figure 1 is a view in side elevation of the machine showing my invention with some details omitted.

Fig. 2 is a similar view showing the mixing drum on its way to charging position during which movement it receives the water.

Fig. 3 is a similar view showing the charging position of the drum.

Fig. 4 is a detail view with parts in section looking from the discharging side of the machine.

Fig. 5 is a fractional detail illustrating part of the means for actuating the water tank.

In the views 6 designates the frame upon which is supported to oscillate a frame 7 pivotally carrying the mixing drum 8. In such machines the drum is provided with suitable means for rotating it on its pivot for the purpose of performing the mixing operation, but as such means are well understood and do not constitute the present invention it seem unnecessary to show or de-

scribe the same in full details. Usually such means typically includes a ring 8^a on the drum engaged by a driving member 8^b, the arrangement being such that the axis 60 of the driving member 8^b coincides with the axis of oscillation of the drum.

Secured to one trunnion of the oscillating drum-supporting frame 7 is a large worm gear 9 engaged by a worm 10 on a shaft 11 65 mounted on the side of the frame 6. The worm shaft 11 has loose on it two bevel gears 12 and 13 engaged by an intermediate driver gear 14. Keyed to the shaft 11 but sliding thereon are clutch members 15 and 16 actuatable by an oscillatory frame 17 having pins to engage grooves in the clutch members 15 and 16 to operatively connect one or the other of said bevel gears 12 and 13 with the worm shaft 11 and so cause said shaft to rotate in one direction or the other according to which of said clutches is so connected. With the machine as shown the intermediate driver 14 during operation rotates constantly in the direction indicated by the arrow. The 80 frame 17 is connected by a link rod 18 with a bent hand lever 19 fulcrumed on pin 19^a on the frame 6 for shifting the clutch members as hereinafter described. The hand lever 19 at its lower end is held on its fulcrum pin yieldingly outward by a spring 19^b and said lever extends upward across the face of the worm gear 9. The face of the worm gear adjacent the hand lever is provided with three lugs 20, 21 and 22 arranged to automatically shift the lever into the neutral or unclutched position of the clutches to stop oscillation of the drum in the position to which it may be destined by the manual operation of the lever. Assuming that the normal position is that illustrated in Fig. 1 the stop 20 is shown as having acted to shift the clutches into neutral position and the drum stopped at discharging position. By shifting the lever to the 100

105 left to engage the clutch 15 the drum is left to engage the clutch 15 the drum is swung as shown in Fig. 2 over to the left or charging position as shown in Fig. 3 at which time the lug 21 strikes the hand lever and throws the clutches into neutral position thereby automatically stopping the movement of the drums and leaving it at the charging position for the supplying of the dry materials. In mixing the concrete after charging it is important that the drum be 110 left stationary, except as to rotation on its axis, with its open end upward for a suff-

cient period of time for the purpose, hence after the lever has been moved to the right from the position as shown in Fig. 3 and the drum started to the right, the stop 22 upon striking the hand lever shifts the same thereby moving the clutches again to neutral position consequently stopping the motion of the drum to the right and at about position shown by broken lines Fig. 3. This last position is termed the mixing position. From the mixing position and after the mixing has been satisfactorily accomplished the hand lever is pulled out a little beyond the stop 22 and again by hand shifted to the right thereby moving the proper clutch into engagement and causing the drum to continue in motion toward discharging position as in Fig. 1. The worm gear 9 in turning from the discharging position to charging position merely carries lug 22 under the hand lever and without actuating said lever and the clutches, said lug being beveled in the direction of the lever when viewed as at the side shown in Fig. 1 and as indicated at 22 in Fig. 4 so as to wedge under the lever without throwing it sidewise.

Suitably journaled above the path of movement of the feeding and discharging opening of the mixing drum is a water tank 30 or vessel 25 supplied by a pipe 26 extending as a rotatable part 26^a to within the vessel where it is provided with a valve contained in a casing 27. The stem 28 of the valve in the casing 27 is provided with a pan float 29 adjustably secured thereto by a set screw so that the amount of water to be admitted to the tank can be regulated. The construction of the valve is such that when the float 29 is raised by the water accumulating in the tank the valve is raised and the water cut off. The water is also held cut off when the tank is inverted and emptied. The tank is rotated by means of a sprocket belt 30 running around a sprocket wheel 31 on the tubular shaft of the drum and a sprocket wheel 32 on a shaft 33. On the shaft 33 is loosely journaled a small spur gear 34 meshing with the large gear 9. The small spur gear 34 has upon its outer face a circular ratchet tooth 34^a; and the shaft 33 has affixed to it a frame 35 carrying a pin 36 backed by a spring 37 tending to project the end of the pin into the path of the tooth 34^a. The construction and timing of the parts is such that during the oscillation of the mixing drum from its discharging position to its charging position the water tank is given a complete revolution thereby permitting the discharge of the water from that tank into the mixing drum and the restoration of the tank to its upright and normally stationary position. In its upright position the tank is automatically resupplied with water. When the water tank is being turned to up-

right position any considerable water in the pan float 29 flows out so that by the time the tank is in upright position the pan is ready to function as a float to cut off the supply from the feed pipe 26^a when the predetermined quantity of water has run into the tank. Contact of the revolved stem 28 with a cam plate 28^a insures that the valve in 27 be opened to supply water to the vessel. When the drum is oscillated from charging position to the mixing or discharging position the water tank is not actuated because the ratchet tooth 34^a is turned in reverse direction.

The forms of the parts can be changed without departing from the gist of the invention as claimed.

What I claim is:

1. In a mixing machine, the combination with a mixing drum having an opening for the reception of the materials to be mixed and means for oscillating the same from discharging position to charging position, a water vessel mounted on a fixed axis to swing above the path of the opening of the drum and intermediate the said charging and discharging positions of the opening of the drum and driven means for automatically turning said water vessel to discharge water into the mixing drum when the latter is moving from discharging to charging position.

2. In a mixing machine, the combination with a mixing drum having an opening for the reception of the materials to be mixed and means for oscillating the same from discharging position to charging position, a water vessel mounted on a fixed axis to swing above the path of the opening of the drum and intermediate the said charging and discharging positions of the opening of the drum, means for automatically supplying a measured quantity of water to said vessel and driven means for automatically turning said water vessel to discharge water into the mixing drum when the latter is moving from discharging to charging position.

3. In a mixing machine, the combination with a water vessel mounted on a stationary axis, a pivotally mounted mixing drum having an opening for the reception of the materials to be mixed and means for oscillating the same in a path under and beyond each side of said water vessel, said means comprising a worm wheel, a worm and shaft therefor, a driver, a reversible clutch mechanism for rotating the worm shaft, a hand lever for actuating the clutch mechanism to cause the oscillation of the mixing drum in either direction, lugs on the worm wheel for actuating said hand lever to throw the clutch mechanism into neutral position and thereby automatically limit the oscillation of the mixing drum in either di-

- rection, and means actuated by said worm wheel for rotating said water vessel to dis-
charge the same when the opening of the
mixing vessel is under the water vessel.
- 5 4. In a mixing machine, the combination
with a pivotally mounted mixing drum hav-
ing an opening for the reception of the
material to be mixed and a water vessel
having a fixed axis under which the mixing
10 vessel oscillates, of means for oscillating
the mixing vessel into charging, mixing
and discharging position comprising a
worm wheel, a worm and worm shaft there-
for, a driver, a reversible clutch mechanism
15 for rotating the worm shaft, a hand lever
for actuating the clutch mechanism to cause
oscillation of the mixing drum in either di-
rection, and three lugs on the worm wheel
for actuating the hand lever to shift the
clutch mechanism into neutral position and 20
thereby automatically limit the travel of the
mixing drum at each of its three said posi-
tions.
5. In a concrete mixing machine, in com-
bination, a water supplying vessel having 25
substantially a fixed axis of rotation, a mix-
ing vessel having a single opening for
charging and discharging it, means for os-
cillating the mixing vessel to move said
opening from a charging position to a dis-
charging position in a path extending un-
der and beyond the water supplying vessel
and means operated by the means for oper-
ating the mixing vessel for discharging the 30
water supplying vessel into the mixing
vessel. 35

GEBHARD JAEGER.
